UNITED STATES PATENT OFFICE.

HENRY HALL, OF LOWELL, MASSACHUSETTS.

DIRECTION-INDICATOR.

1,261,228.

Specification of Letters Patent.

Patented Apr. 2, 1918.

Application filed October 1, 1914. Serial No. 364,497.

To all whom it may concern:

Be it known that I, HENRY HALL, citizen of the United States, residing at Lowell, in the county of Middlesex and State of Massachusetts, have invented certain new and useful Improvements in Direction-Indicators, of which the following is a specification.

This invention relates to direction indicators, and more especially to that type of such devices as are meant to be adjustably carried by motor vehicles in city streets to signal to each other future movements of the traffic units individually.

As a principal object, it is contemplated by this invention to provide a device of the character described which shall reliably indicate at a moment's notice the direction to be taken by the vehicle carrying such device to observers both in advance and to the rear of the machine and which will also signal to following cars whenever a stop is intended.

It is a further object to provide a traffic indicator of the type set forth which shall be easily operated by the driver of the car and which shall be equally useful in night time as well as daylight.

It is a further aim to provide a device of this kind which may be readily positioned upon an automobile without necessitating any alteration in the construction of the same and one that when so positioned will not take up a great amount of space, will have the majority of its working parts hidden and will not detract from the beauty of any car.

An object of equal importance with the foregoing is to so construct a direction indicator accomplishing the foregoing object with such regard to proportion, number and arrangement of parts as to render it capable of being cheaply manufactured as well as durable and efficient in operation.

The above and additional objects which will become apparent as this explanatory description proceeds are accomplished by such means as are illustrated in the accompanying drawings, described in the following specification and then more particularly pointed out in the claims which are appended hereto and form a part of this application.

With reference to the drawings, wherein there is illustrated the preferred embodiment of this invention as it is reduced to practice, and throughout the several views of which like characters of reference designate similar parts:

Figure 1 is a side elevation of an automobile body showing the improved direction indicator comprehended by this invention positioned thereupon,

Fig. 2 is an enlarged and longitudinal partial section of the matter disclosed in Fig. 1,

Fig. 3 is a perspective view of the forward indicating frame,

Fig. 4 is a side elevation of the rear frame,

Fig. 5 is a plan view of the operator's control,

Fig. 6 is a sectional detail taken on the plane indicated by the line 6—6 of Fig. 5,

Fig. 7 is a similar view taken on the plane 7—7 also shown in Fig. 5,

Fig. 8 is a view taken on the line 8—8 of Fig. 2.

Upon reference to the drawings, the numeral 10 designates the body of an automobile mounted as is customary upon chassis or frame members 11. U-shaped frames illustrated more particularly in Figs. 3 and 4 are used for mounting the various indicators employed by this invention, the frame 12 being secured to the radiator or hood of the automobile in any desirable manner while its companion frame 13 is carried by the very rear of the machine in a situation analogous to the tail-light. The free ends of each U-shaped frame are threadingly apertured to receive a similarly threaded plug 14, each of which plugs has its inner end conically recessed to receive a similarly shaped extremity of rotatable rods 15 which are held removably and adjustably between the extremities of the U-shaped member.

The rod 15 carried by the frame 12 is provided with an indicating device 16 which as illustrated preferably takes the form of a hand with the index finger outstretched, such device being formed from a cheap and durable metal and fixedly secured to the rod 15 for rotation therewith. A sleeve 17 has formed thereon an arcuate arm 18, one end

of which is connected by a link 19 to the upper end of a lever 20 which is pivoted as at 21 to a small L-shaped bracket 22 carried by the lower arm of the frame 12. The lever 20 at its opposite extremity has connected thereto the link 23 which as will herein-after be described forms a portion of the intermediate transmission of actuating power to the indicator 16. In order to maintain this latter in the position illustrated so as to normally indicate the straight forward direction of the machine, a suitable resilient means such as the contractile coiled spring 24 is provided to perpendicularly connect the oscillatable rod 15 with the body portion of the U-shaped frame 12 so that any tendency toward rotation on the part of the former will be resisted by the tension of the spring.

20 The upper arm of the U-shaped frame carries a pair of U-shaped contact poles nested one within the other but insulated so that the pole 25 to which is connected a lead wire 26 cannot establish any communication with the inner pole 27 whose lead wire is numbered 28 without the interposition of further means which in this case may preferably include an arm 29 carried by the rotatable rod 15 and projecting into the space inclosed by the U-shaped arm 27 so that rotation of the rod in either direction will contact it with the pole 27 and force it into contact with the pole 25. A lamp 30 of any usual construction provided with a filament becoming incandescent at a low voltage is removably secured into a bracket 31 carried on each frame and has the wire 26 in circuit therewith. Reflectors 32 are also provided for each lamp in order to direct the illumination upon the indicating fingers 16.

The rear frame 13 has its rod 15 similarly equipped with an indicating device 16, sleeve and arm 17 and 18, link 19, lever 20, spring 24 and similar adjuncts in the manner already described for the forward frame. Since both lamps 30 are adapted to be "on" simultaneously to properly show the similar movements of both signaling hands, no make and break contact such as the arm 29 and U-shaped poles 25 and 27 are needed on this rear frame. Means however are provided to signal to a following car an intended stop of the first car, such means including a vertically swinging indicating hand 33 pivoted as at 34 to a suitable bracket carried by the frame 13 and normally held in the horizontal or non-registering position indicated in Fig. 4 by means of the contractile spring 35. Connections 36 are interposed between a free end of the stop indicator and a T-lever 36 which is pivoted as suitably illustrated at 37 to the frame 13 and is connected with primary means of

actuation therefor as will be more clearly set forth.

There is illustrated in Fig. 5 control means for the various indicating devices including a U-shaped member 38 riveted to a plate 39 adapted to be secured to the inclined dash of the automobile, said member carrying the rotatable sleeve 40 centrally of which and at right angles to which are suitably fastened pedals 41 and 42 preferably provided with the characters "L" and "R" 75 to indicate respectively a left or right turn of the machine. Ears 43 project rearwardly of the bracket 38 and have pivoted thereto an L-shaped lever 44 suitably marked "S" 80 and designed to operate the mechanism indicating a stoppage of the vehicle, projecting for this purpose through a suitable slot 45 in the base plate.

The base plate 39 is laterally slotted as indicated at 46 and registering therewith is a similar aperture 47 formed in the U-shaped bracket 38 so that a depression of either of the arms 41 and 42 will result in arcuate movement transversely of the machine of the depending stem 48 which is formed with the pedals above described and mounted with the rotatable sleeve 40 for oscillation through these slots. The lower end of the stem 48 receives the connecting rod 49 whereby the transverse movement of the stem may be transmitted to a three-way connecting lever 50 as a longitudinal movement which through any suitable number of levers 51 of the first class may finally be depended upon to actuate the lever 20 carried on the forward U-shaped frame 12 through the medium of the link 23. The three-way connecting lever 50 as illustrated in Fig. 1, which is shown T-shaped, has a point of connection shown at the free end of its shank 100 for a rod 52 which extends rearwardly and by successive connections with a number of levers 51 of the first class similar to those carried on the forward part reaches the rearmost link 23 and through the rear lever 110 20 actuates the indicator 16 carried by the frame 13 in the same manner and simultaneously with the pointer mounted on the forward frame.

In order to clearly ascertain the manner 115 in which depression of the respective pedals 41 and 42 produces in turn opposite longitudinal movements of the connecting rods reference should be had to Fig. 8. In this figure, it will be noticed that the connection 120 49 between the stem 48 and the initial lever 50 is diagonally positioned with respect to the car since the levers 50 and 51 are adapted to be pivoted on suitable T-brackets 53 carried by one of the frame members 11 of 125 the chassis which of course would place them far to the side of the longitudinal medial line. When the lever marked "L"

is thus depressed the stem 48 is swing to the right which as will readily be seen upon reference to this figure lengthens the distance between the end of the stem and the 5 initial lever 50 which latter must of course move rearwardly in response to the pull of connection 49, such rearward pull being transmitted as explained to the arm 18 whereby the rod 15 is with its indicating 10 hand 16 turned through a small angle from right to left in both of its frames 12 and 13 simultaneously indicating the immediate new course of the machine.

Conversely a depression of the lever 15 marked "R" will swing the stem 48 to the left thereby lessening the distance between the end of said stem and the normal position of the lever 50 resulting in a forward push upon that lever and a consequent rotation 20 of each rod and indicating hand in a slight arc from left to right.

The connections for the stoppage indicating pedal marked "S" and designated 44 are of a much simpler nature since the pull to be 25 exerted in this instance upon the hand 33 is always in but the one direction so that small T-levers 54 are pivoted to a succession of brackets 55 and leading directly to the rear lever 36 and thence by way of the connections 36' to the indicator 33 which is immediately displaced against the tension of the 30 spring 35 upon depression of this pedal 44.

A lever for controlling the illumination 35 of indicators include in addition to the customary T-shaped body portion 56 an angular and downwardly turned extension 57 which is adapted to act as a switch blade between the contact plates 58 upon proper operation of the lever 56 for the purpose of 40 providing a contact in the lamp circuit.

It will be noted that various adjusting devices 65 may be interposed between pairs 45 of adjacent levers 51 in order to take up any strain or wear upon the connecting rods or to properly position the latter so that equal pulls will be exerted upon the indicators 16.

The operation of the improved direction 50 and stoppage indicator herein disclosed will be readily discernible from the foregoing detailed description in which it will be seen that means have been provided whereby the objects previously set forth may be accomplished and that accordingly this invention 55 may be claimed as possessing the advantages above recited which are attained in this or an equivalent manner.

What is claimed is:—

1. The combination with a vehicle; of forward and rearward frames, an oscillatable 60 rod journaled in each frame, an indicator carried by each rod, an arm projecting from each rod, levers of the first class alined between the frames, connections between said arms and levers, connections between said

levers to operate said indicators in unison, 65 and a three-way connecting lever interposed in said lever alinement and connected with said first mentioned levers for manual operation of both indicators.

2. The combination with a vehicle; of forward and rearward frames, an oscillatable rod journaled in each frame, an indicator carried by each rod, an arm projecting from each rod, levers of the first class alined between the frames, connections between said 70 arms and levers, connections between said levers to operate said indicators in unison, a three-way connecting lever interposed in 75 said lever alinement and connected with said first mentioned levers for manual operation of both indicators, and a rock arm oppositely movable to simultaneously move the indicators in desired directions.

3. The combination with a vehicle; of forward and rear frames carried thereby, an oscillatable rod positioned in each frame, an indicator carried by each rod, an arm projecting from each rod, and fixed thereto, a series of levers of the first class arranged 35 in substantial alinement between the frames, rods connecting said levers, links connecting said arms with the end levers of said series, and means interposed between said levers and manually operable for actuating 40 both indicators.

4. The combination with a vehicle, of forward and rearward frames, an oscillatable rod mounted in each of said frames, a movable indicator carried by each rod, an arm projecting from each rod, connecting levers 100 and rods between the frames, connections between the levers to operate the indicators, and a three-way connecting lever interposed 105 between said rods and levers for manual operation of both indicators.

5. The combination with a vehicle, of forward and rearward frames, an oscillatable rod journaled in each frame, an indicator carried by each rod, an arm projecting from each rod, levers of the first class alined 110 between the frames, connections between said arms and levers, connections between said levers to operate said indicators in unison, a three-way connecting lever interposed in 115 said lever alinement and connected with said first mentioned levers for manual operation of both indicators, a rod connected at one end with said three-way lever, a pedal mounted to rock on said vehicle and having an arm connected with the other end of said 120 rod whereby the rocking of said pedal in one direction or the other will operate to simultaneously actuate said indicators.

6. The combination with a vehicle, of forward and rearward frames, an oscillatable 125 rod journaled in each frame, an indicator carried by each rod, an arm projecting from each rod, levers of the first class alined be-

24
tween the frames, connections between said arms and levers, connections between said levers to operate said indicators in unison, a T-shaped three-way lever interposed in said lever alinement with one arm connected with said first mentioned levers at the front of the vehicle and the shank thereof connected with the levers at the rear, a rod connected at one end with the other arm of said three-

way lever, and an actuating pedal connected to with said rod.

In testimony whereof I affix my signature in presence of two witnesses.

HENRY HALL.
